UNITED STATES PATENT OFFICE.

RANDOLPH B. HANCOCK AND GEORGE SIPPLE, OF BALTIMORE,
MARYLAND.

SCREEN.

SPECIFICATION forming part of Letters Patent No. 729,577, dated June 2, 1903.

Application filed August 7, 1902. Serial No. 118,756. (No model.)

To all whom it may concern:

Be it known that we, RANDOLPH B. HANCOCK and GEORGE SIPPLE, citizens of the United States of America, and residents of 5 Baltimore, in the State of Maryland, have invented certain new and useful Improvements in Screens, of which the following is a specification.

This invention relates to certain new and 10 useful improvements in screens, and, as will hereinafter appear, it is applicable to screens for doors or windows as well as other places where it is desirable to keep out flies and to induce those already within the inclosure to 15 pass out of the same.

The present invention has for its objects, among others, to provide an improved form of screen door or window by means of which the flies and other insects alighting upon the 20 screen, either upon the outside or inside of the door or window, are induced to pass through openings in the screening in a trap included between the outer and inner faces of the screen, from which they may be readily removed at any time desired.

The present construction embodies in its broadest sense a double screening having a space therebetween and the double screening being provided with passages or openings 30 communicating with the said space and the screen provided with channels or the like leading to said openings and by which the flies are induced to pass through such openings into the trap, from which latter they cannot escape. One portion of the screen is 35 removably mounted, so as to provide access to the interior of the trap formed by the two screens. The channels may be disposed vertically, horizontally, or otherwise, their function being the same. The channels formed 40 in the two screens are alternately arranged, so that the openings in the one channel will be disposed opposite the screening intermediate two channels on the opposite side of 45 the door or window.

It is to be understood that it is not necessary to bait the trap and that the flies may be readily removed therefrom when desired without allowing them to escape into the room.

Other objects and advantages of the invention will be hereinafter described, and the

novel features thereof will be particularly pointed out in the appended claims.

The invention in its preferred form is clearly illustrated in the accompanying drawings, which, with the numerals of reference marked thereon, form a part of this specification, and in which—

Figure 1 is an elevation of a screen-door embodying our invention. Fig. 2 is a similar 60 view of another form. Fig. 3 is a cross-section on the line 3-3 of Fig. 1. Fig. 4 is a face view showing the embodiment of the invention in a window-screen. Fig. 5 is a detail view, on an enlarged scale, showing a portion 65 of the screen to illustrate the manner of closing the end of the channel. Fig. 6 is a view of such screen material before being folded, showing the slits therein. Fig. 7 is a bottom view of a window-screen, showing a movable 70 bottom piece for permitting access to the interior of the trap. Fig. 8 is a perspective view of a portion of the screen material, illustrating the manner of closing the end of the channel. 75

Like numerals of reference indicate like parts in the several views.

Referring now to the details of the drawings, 1 designates the frame, in Fig. 1 represented as that of a screen-door, and 2 designates the wire-netting, which may be affixed in position thereon in any suitable manner. In this instance it is shown as seated in a rabbet 3 in the frame and a securing-strip 4 placed thereover and secured in the well-known way; but the manner of securing the wire-netting to the frame is immaterial, and any suitable means may be employed. This screen material is formed with a series of channels 5, which are substantially V-shaped 85 in cross-section, as seen in Fig. 3, and these channels are provided at intervals with openings 11, as shown. These channels may extend vertically, as indicated in Figs. 1 and 2, or horizontally, as seen in Fig. 4, or otherwise, as may be deemed most expedient.

7 is a frame, hinged at 8 to one side of the frame 1, as seen in Figs. 1 and 3, and to the outer face of this frame is secured the netting 9, having a series of V-shaped channels 10, which are provided with a series of openings 6, as seen best in full lines, the openings

11 in the screening on the stationary frame being indicated by dotted lines in Fig. 1. This hinged frame may be provided with suitable means, as hooks 12, for holding it in position upon the frame 1. It will thus be seen that a space 13 is provided between the screen materials 2 and 9, which forms a trap into which the flies pass through the openings 6 and 11 in the said screen materials. It will be noted, as seen best from Fig. 3, that the channels 5 and 10 in the two screen materials are alternately arranged—that is, the channel of one is disposed opposite the material between the two adjacent channels of the opposite screen material. This provides increased space and disposes the openings 6 and 11 out of alignment with each other. This alternating or zigzag disposition of the channels is maintained whether the channels extend vertically, horizontally, or otherwise.

From the above it will be seen that we provide a simple and cheap construction of screen, suitable for door or window, in which a trap is provided, into which the flies or other insects are led through the openings in the opposite screen materials and from which space the flies may be removed at any desired time by simply moving the screen 7 upon its hinges. It is not necessary to place any bait in the trap, and as the bottoms of the channels, as well as the tops thereof and the top and bottom of the trap, are closed the flies after once entering the same cannot escape.

The construction seen in Fig. 2 is substantially the same as that in Fig. 1, except that the frame 7 is of somewhat different construction, and we wish here to state that we do not restrict ourselves to the form or style of the door or of the hinged frame thereto.

In Fig. 4 we have shown the application of the invention to a window, in which view 14 designates the frame, 15 the outer screen material, 16 the openings, and 17 the openings in the other screen material, the construction and mode of operation being essentially the same, except that in this form we make the bottom 18 of the frame movable, hinging it at 19 and providing any suitable means for holding it closed. It will be readily understood that the opening of this bottom portion discloses the bottom of the trap or space between the inner and outer screen materials, so that the flies may be readily shaken or otherwise removed therefrom.

Referring now to Figs. 5, 6, and 8, the manner of closing the ends of the channels will be readily understood. Referring first to Fig. 6, it will be seen that the material is slotted by three parallel slits 21, and when the material is placed in position on the door or window frame the portions 22 and 23 upon opposite sides of the central slit are bent diagonally and caused to overlap, as indicated, forming the triangular doubled portion 24, which constitutes the bottom of the channel, as seen more clearly in Fig. 3, and the portions extending beyond this overlapped triangular

part are engaged beneath the beading-strip or other means which serves to secure it firmly in place.

From the above it will be seen that we have devised a cheap, novel, yet efficient screen for the purposes described, and while the structural embodiment of the invention as herein disclosed is what we at the present time consider preferable it is evident that the same is subject to changes, variations, and modifications without departing from the spirit of the invention or sacrificing any of its advantages, and we therefore do not wish to be restricted to the details of construction herein disclosed, but reserve the right to make such changes, variations, and modifications as come properly within the scope of the protection prayed.

What is claimed as new is—

1. In a screen for a door or window comprising a double screen-surface with a space therebetween and communication with said space from both of said surfaces, said screen-surfaces being provided with channels with openings leading through said channels into said space and closures for the ends of said channels formed integral with the screen-surface, substantially as described.

2. A screen for a door or the like comprising a relatively fixed screen with openings, and a relatively movable screen arranged with a space between them, said screens being provided with channels and openings leading therefrom communicating with said space said channels being alternately disposed and having integral closures at the ends.

3. A screen for a door or window comprising a relatively fixed screen with channels and openings, a relatively movable screen with channels and openings leading therefrom, and closures at the ends of said channels integral with said screens, said screens being arranged at a distance apart with the channels of one arranged opposite the surface intermediate the channels of the other and means for closing the ends of the space between said screens.

4. A screen for a door or the like comprising a relatively fixed screen having channels with inclined walls and openings with the ends of said channels closed by the material of the screen, a movably-mounted screen-surface having channels with inclined walls and openings leading therefrom with the ends of the channels closed by the screen-surface, the channels of the one screen alternating with those of the other and the movable section adapted to be moved to provide access to the trap formed between said screen-surfaces.

Signed by us at Baltimore, Maryland, this 6th day of August, 1902.

RANDOLPH B. HANCOCK.
GEORGE SIPPLE.
